UNITED STATES PATENT OFFICE.

HENRY TIDEMAN, OF MENOMINEE, MICHIGAN.

TRANSMITTER FOR THE DEAF.

1,036,933.

Specification of Letters Patent. Patented Aug. 27, 1912.

Application filed June 11, 1909. Serial No. 501,495.

To all whom it may concern:

Be it known that I, HENRY TIDEMAN, a citizen of the United States of America, and a resident of Menominee, county of Menominee, and State of Michigan, have invented a new and useful Improvement in Transmitters for the Deaf, of which the following is a specification.

My invention pertains to electrical speech-transmitting devices of design suitable for collecting sounds from any distance, and transmitting electrical waves as controlled thereby, particularly to types designed to be carried upon the person and forming parts of systems for assisting the hearing of persons having this sense impaired.

In telephone transmitters of the carbon type, whether of the granular carbon structure or of some other design, difficulty is encountered in producing a universal instrument which will be adapted without specific adjustment to sounds either strong or weak and located either near or distant from the transmitter, or located either directly in front or at a considerable angle from the front of the transmitter. The transmitter adapted to receive and interpret electrically sounds which are minute in volume will be found to blare when the sound waves impinge upon its diaphragm with too great energy. Such a transmitter is found in the old Blake instrument, mounted in its wood box. On the other hand, instruments so constructed mechanically as to withstand rigorous conditions of sound waves upon their diaphragms usually are insensitive to the waves of smaller volume and to the finer modulations of the voice waves. The structure of my invention operates to equalize upon the diaphragm the sound waves received by the instrument, to prevent the blaring of the instrument under violent sound action and to render it insensitive to minute sound waves which may reach it.

With a given distance from the speaker's lips to the telephone transmitter, the effective energy of the sound waves, where a transmitter of ordinary construction is considered, varies with the change in the angle between the line normal to the transmitter diaphragm, and a line from the center of the diaphragm to the speaker's lips. When the speaker is in line with the normal of the diaphragm, the sound waves of his speech are most effective in operating the

transmitter. When he speaks to the transmitter from a considerable angle, say 40 or 60 degrees, his speech has but a small fraction of its normal efficiency. I equalize this variation by a system of reflecting and obstructing means in my improved transmitter.

A transmitting resistance constructed and adjusted to appreciate minute sound waves has been impracticable for general use by reason of the blare resulting when the transmitter is spoken into directly. I make possible the successful use in practice of a transmitting mechanism so designed and constructed as to respond to smaller sound waves, my device for so doing consisting first of obstructing features whereby speech directed too strongly into the transmitter will be held subdued to a volume suited to the very sensitive transmitters and consisting further of reflecting surfaces and conducting channels whereby sound waves proceeding from considerable angles are permitted to reach the diaphragm without loss of efficiency and to produce a response in the transmitter.

The transmitter, constructed in accordance with the principles above outlined, is responsive to sounds arising within a wide angular range. This feature, at times very desirable, is at other times somewhat objectionable, since an afflicted person may desire to concentrate the sound collecting abilities of his transmitter upon the voice of a single person rather than upon the utterances of all of an assembled company. To supply this requirement of a transmitter, I provide an auxiliary device or attachment which I term a concentrator. This device has the effect of rendering the transmitter responsive only to sounds arising within a smaller angle and makes the transmitter more fully responsive to sounds arising within the more limited angle. The concentrator I prefer to make in the form of an attachment which may be placed upon the transmitter or removed therefrom at will, although, of course, it may be built integrally with the transmitter, if so desired.

My improved transmitter comprises a chamber containing a very sensitive carbon cell, presenting its principal sound receiving diaphragm toward the front. The front of the chamber is perforated centrally with small holes and also with large

holes near the edge. Within the chamber are two truncated cones of sheet metal, one within the other, and both tapering from the front wall of the chamber. The outer of these cones reflects from its inner surface, and the inner reflects both from the outer and inner surfaces. Sounds entering from considerable angles are passed by the reflections of the cones to the diaphragm, the paths being such as to cause the sound waves to impinge upon the diaphragm at angles less inclined to the vertical than the original direction of the sound waves, thereby increasing the effect upon the diaphragm of the diagonal sound waves which ordinarily are less effective upon the transmitter. After two reflections, or any even number of reflections from parallel surfaces, sound has again its original direction, but where the surfaces are not parallel, the ultimate direction of the sound is changed. To secure this effect as an advantage in my improved transmitter, I make the reflecting cones of different degrees of inclination to their axes, the outer cone having the greater inclination to its axis.

The transmission of sounds received diagonally is principally through the large holes in the face of the transmitter near the periphery. When my concentrator is applied to the front of my transmitter, the effect of the large outside holes in the transmission of sounds from wide angles is greatly reduced, as sounds reaching those openings must do so through the ring of holes in the face of the concentrator near the periphery. The angle of the sounds which may reach the diaphragm by this path is much smaller than the angle accommodated without a concentrator. In addition the sounds from directly in front are passed through the outer openings of the concentrator and the outer openings of the transmitter face plate, and thence to the diaphragm.

The following drawings, in which like labels refer to like parts throughout, accompany and form a part of these specifications.

Figure 1 shows front view of my assembled transmitter and concentrator. Fig. 2 shows sectional view of same on the line 2-2 of Fig. 1. Fig. 3 shows side view of same. Fig. 4 shows front view of my improved transmitter with the concentrator removed. Fig. 5 shows section of my improved transmitter alone, indicating the handling of sounds received from different directions. Fig. 6 shows section of my improved transmitter and concentrator, and shows the handling of sound received from different directions.

In Fig. 5, lines 32, 33, 34 and 35 show the action of the reflecting surfaces of the transmitter upon sound passing through the openings of the face plate in a direction

perpendicular to the transmitter diaphragm 4'. Lines 32 through opening 7 is turned back abruptly. Line 33 through opening 7 suffers many reflections between the two surfaces. Line 34 through opening 8^a is turned back upon itself. Line 35 through the central opening 8^b is passed without obstruction to the diaphragm 4'. The diagonal line 31, however, is reflected by part 6 and then by part 5 and reaches the diaphragm 4' in a direction more nearly perpendicular to the plane of the diaphragm. Line 31 is about the maximum of diagonal line showing the angle at which sound may reach the transmitter and be carried effectively to the diaphragm 4'. 70 75 80

In Fig. 6, the lines 43, 45 and 47 show the action of the device upon sound perpendicularly related to the diaphragm. The line 47 through opening 13^b proceeds uninterruptedly to the diaphragm. Diagonal lines 44 and 46 through openings 13^a and 13^b also pass uninterruptedly to the diaphragm. Diagonal line 42 is doubly reflected and shows the change in angle which is provided for in my invention, the line 42 after reflection being more nearly perpendicular to the diaphragm than before reflection. Line 41 is about the maximum of diagonal line showing the angle at which sound may reach the transmitter diaphragm through the concentrator efficiently. 85 90 95

The transmitter case consists of front plate 1, having the annular edge 2 forming a box-like receptacle. This is closed by back plate 3. On the back plate 3 is mounted the transmitter cell 4, which may be of any design responsive to minute sound waves and minute voice inflections but which I prefer to make in accordance with general principles and details set forth in my application for United States Patent No. 453,350; filed September 16, 1908, for telephone transmitter.

To the face plate 1 is secured the inner cone 5, and between the face plate 1 and the rigid metallic case of the transmitter 4 is clamped the sheet metal reflecting truncated cone 6. The location of the large openings is indicated in Fig. 2 upon dotted lines at 7. 110 115 The central openings 8 lie within the inner truncated reflecting cone.

My concentrator comprises a face plate 10, and an annular portion 11 mechanically united. Upon the inside of face plate 10 is secured the truncated cone 12. A system of smaller perforations 13 is located within the truncated cone, and a system of larger perforations 14 is located in the face plate outside of the cone. 120 125

The annular portion 2 of the transmitter is provided with rib-like feet 2', 2'', and with an upper lug 2'', which carries terminals 10 for the leading-in conductors. Annular portion 11 of the concentrator is of 130

proper size to slip closely over the cylindrical transmitter case and is so conformed on its edges as to engage projections 2', 2", and 2'" to determine its proper position upon the transmitter case.

5 I do not wish to limit my invention to the specific structure herein described and illustrated.

What I claim as new and desire to secure 10 by United States Letters Patent is:

1. In a transmitter, a sound responsive resistance cell, and a set of concentric conical reflecting surfaces, each a truncated cone tapering toward said resistance element.

15 2. In a transmitter, a sound responsive resistance cell, and a set of concentric conical reflecting surfaces, each a truncated cone tapering toward said resistance element, said reflecting surfaces being coaxial and 20 having their axes normal to the sound receiving diaphragm of said sound responsive device.

25 3. In a transmitter, a case comprising front and back plates; sound responsive apparatus mounted rigidly upon said back plate; and a set of sound reflecting truncated cones within said transmitter case, and positioned between said front plate and the sound responsive device.

30 4. In a transmitter, a case comprising a front plate and a back plate; a transmitter cell mounted upon said back plate rigidly; and a set of sound receiving cones engaging said front plate and said transmitter cell, 35 and clamped between them.

40 5. In a transmitter, a perforated front plate; a sound responsive cell mounted in the rear thereof; and two truncated cones between said front plate and said transmitter; said front plate having two systems 45 of perforations, one system within the base of the inner cone, and the other system between the inner and outer cone.

6. In a transmitter, a sound receiving diaphragm; a case inclosing said diaphragm, said case having two systems of apertures; reflecting surfaces coöperating with said apertures to conduct diagonally received sound waves into impingement with said 50 diaphragm more efficiently than normally received sound waves.

7. In a transmitter, two coaxial reflecting conical surfaces, the outer of which has a greater inclination to its axis than the inner.

55 8. In a transmitter, two coaxial truncated reflecting conical surfaces, the outer of which has a greater inclination to its axis than the inner.

9. In a transmitter, a concentrator, comprising a face plate and a set of concentric truncated cones attached to the inner surface thereof.

10. In a transmitter, a concentrator comprising a face plate perforated with two 60 systems of holes; and a truncated cone at-

tached to the inner surface of the face plate, said two systems of holes being disposed, one system within the base of said cone and the other surrounding the base of said cone.

11. In a transmitter, a transmitter case 70 having projections adapted to form a base for supporting the transmitter case and a projection forming a mounting place for terminals; a concentrator having a flange adapted to surround said transmitter case, 75 the edges of said flange being cut to take seat against the projections of said case to determine the relative position of the concentrator upon the transmitter case.

12. In a transmitter, a series of two perforated face plates, each carrying reflecting cones; and a sound receiving diaphragm, mounted parallel to said face plates and perpendicular to the axis of said cones.

13. In a transmitter, a series of two perforated face plates, each carrying reflecting cones; and a sound receiving diaphragm, mounted parallel to said face plates and perpendicularly to the axis of said cones, each of said face plates being perforated inside and outside of its central reflecting cone and all of said reflecting cones tapering toward said sound receiving device.

14. A sound concentrator comprising a vibratory diaphragm, a frusto-conical deflector located in front of said diaphragm 95 with its smaller end terminating in front of and adjacent thereto and a relatively small deflector concentrically located within said frusto-conical deflector with its 100 smaller end also adjacent to said diaphragm.

15. A sound concentrator comprising a case, a diaphragm supported within and adjacent to the bottom of said case, a frusto-conical deflector projecting into said case 105 from its front end and supported by the edges thereof, and a relatively small deflector concentrically disposed within said frusto-conical deflector with its smaller end adjacent to the smaller end of said frusto-conical deflector.

16. A sound concentrator comprising a case having an open front end, a frusto-conical deflector projecting into the case from its front end, and a centrally located 115 conical deflector of substantially the same depth as said frusto-conical deflector but of relatively small maximum diameter, the lines of both deflecting surfaces being convergent inwardly.

17. A transmitter comprising a metal case, a diaphragm mounted upon the base of said case, two concentric conical deflectors projecting into said case from its forward end and having inwardly converging surfaces that terminate adjacent to said diaphragm, and means for imparting the vibratory influence of said diaphragm to an electric circuit.

18. A sound transmitter comprising a cy- 130

lindrical case having an open front end, a vibratory diaphragm supported within said case, and means for directing and deflecting forwardly against the central part of said 5 diaphragm all of the sound waves intercepted by said open end that do not impinge directly against said central part.

Signed by me at Menominee, county of Menominee and State of Michigan, in the presence of two witnesses.
